W. A. STATTMANN

SAFETY SEAL FOR BOTTLES AND THE LIKE

Filed June 9, 1923

Inventor

Walter A. Stattmann

By *Adolph Henning*

Attorney

UNITED STATES PATENT OFFICE.

WALTER A. STATTMANN, OF CHICAGO, ILLINOIS, ASSIGNOR TO PUBLIC SAFETY CAP COMPANY, OF CHICAGO, ILLINOIS, A CORPORATION OF ILLINOIS.

SAFETY SEAL FOR BOTTLES AND THE LIKE.

Application filed June 9, 1923. Serial No. 644,334.

To all whom it may concern:

Be it known that I, WALTER A. STATTMANN, a citizen of the United States, and a resident of Chicago, county of Cook, and 5 State of Illinois, have invented certain new and useful Improvements in and for Safety Seals for Bottles and the like, of which the following is a specification.

This invention has for its object to provide 10 a device for sealing a bottle or similar container to the extent of preventing access to the hermetical seal thereof, such as a cork or similar closure, in order to prevent tampering with the contents of the bottle.

15 The invention relates more particularly to a metallic cap adapted to be so secured to the bottle neck as to render removal thereof without destruction thereof impossible and which is readily severable into two parts by 20 digital engagement of a portion thereof whereby the crown portion of said cap is rendered readily removable for access to the hermetic closure by the consumer of the contents of the bottle.

25 The invention consists in the novel feature of the construction of the cap herein-after fully described and claimed.

In the accompanying drawings illustrating a suitable embodiment of the invention:

30 Fig. 1 is a fragmentary side elevation of a bottle equipped with a cap constructed in accordance with the invention.

Fig. 2 is a fragmentary central vertical section of the same on the line 2—2 of Fig. 1.

35 Fig. 3 is a transverse section of the same on the line 3—3 of Fig. 1, the severing means being shown as partly detached from the cap.

Fig. 4 is a perspective view of the cap before 40 being mounted on the bottle.

The mouth portions of bottle necks are usually provided with tapered exterior circumferential walls as shown at A in Fig. 2, there being an annular groove B below said 45 tapered portion having an annular bead C and a second annular groove D below the groove B.

These features are characteristic of nearly 50 all bottles, the depth of the grooves B and D and the angle of the shoulders bordering the same differing to some extent.

The bottle neck is normally sealed by a cork E or any other suitable hermetic closure and which may, as in the instance illus-

trated, include a crown portion F resting 55 upon the rim of the bottle neck.

The cap of my invention comprises a slightly tapered sheet metal sleeve G conforming in contour approximately with the surface portion A of the bottle neck and being of greater length than the latter so that its lower end portion is adapted to extend over the groove B and bead C and preferably at least partially over the groove D. The other end of the cap is provided with a 60 head H integral with the sleeve G and adapted to cover the closure element E and its crown portion F, if any.

It is an essential feature of the invention 65 that said cap shall be composed of a sheet metal which possesses a certain degree of malleability while at the same time it is sufficiently stiff to resist easy manipulation by ordinary tools. This is more fully explained hereinafter in connection with the operation 70 of the device.

To seal a bottle to the extent indicated above, the cap is placed upon the mouth of the bottle as shown in Figs. 1 and 2, and thereupon the circumferential wall of the 80 cap adjacent its lower end portion is spun by means of a suitable tool or machine provided for the purpose so as to snugly fit the grooves B and D and the intervening bead C. It is thus held there firmly in place upon 85 the bottle neck, the metal being such that any attempt to release the cap from engagement in the grooves B and D, will result in a fracture of the metal and prevent the replacement of the cap upon the bottle neck 90 without rendering clearly visible the fact that it has been tampered with.

The base and crown portions, respectively, 95 of said cap are separated from each other by a ribbon I of the metal which is integral with said base and crown portions, respectively, and is bordered by a pair of parallel substantially annular incisions J which serve to weaken the metal along these lines to such an extent as to permit the ribbon I to be 100 very easily severed from the crown and base portions, respectively, by digital engagement of the tongue K which is integral with one end of the ribbon I and projects into an opening L in the circumferential wall of the cap, said opening being of greater area than said tongue so as to provide a free space around the latter such as will permit the 105

finger nail to be inserted between said tongue and the opposed wall portion of the bottle for the purpose of effecting an outward projection of said tongue to permit its digital engagement with the thumb and index finger, for example, by means of which, without the use of any tool or device, said ribbon 5 I may be severed from the cap to thereby divide the latter into two parts, the upper or 10 crown portion thereof being thus rendered readily removable so as to give access to the hermetic closure of the bottle, while the base portion remains mounted upon the latter.

Obviously, in order that such digital 15 severance of the ribbon from the cap may be effected, the metal of the cap must be readily bendable, and the incisions rendering the severance of the ribbon from the bottle easy, must be relatively deep without, 20 however, rendering the joint between the ribbon and the base and crown portions of said cap so delicate or fragile as to cause the crown portion to be accidentally removed in the ordinary handling of bottles 25 provided with such caps in commerce. I have found aluminum or an aluminum alloy to be very satisfactory for the purpose. The exact location of the ribbon between the ends 30 of the cap is preferably such that after severance of the ribbon from the cap and the removal of the crown portions the lips may be applied to the mouth of the bottle without danger of being cut by the raw or 35 bird edge presented by the remaining base portion.

While I have illustrated and described the preferred form of embodiment of the invention, it will be understood, of course, 40 that such embodiment is capable of being changed and varied in minor details of construction without departing from the invention as defined in the appended claims.

I claim:

1. A bottle seal comprising a sheet metal 45 cap adapted to cover the mouth portion of the bottle and secured thereto for preventing access to the cork or other hermetic closure of the bottle, said cap provided between its ends with a substantially annular strip integral therewith and bordered by substantially parallel incisions for rendering 50 said ribbon easily severable from the cap to thereby divide the latter into two parts, one thereof removable to expose and provide access to the hermetic closure thereof, there being an opening in the cap in the 55 plane of said ribbon, the latter terminating at one end in a tongue projecting into said opening.

2. A bottle seal comprising a sheet metal 60 cap adapted to cover the mouth portion of the bottle and secured thereto for preventing access to the cork or other hermetic closure of the bottle, said cap provided between its ends with a substantially annular

strip integral therewith and bordered by substantially parallel incisions for rendering 70 said ribbon easily severable from the cap to thereby divide the latter into two parts, one thereof removable to expose and provide access to the hermetic closure thereof, there being an opening in the cap in the plane of said ribbon, the latter terminating at one end in a tongue projecting into said opening, the latter being of greater area 75 than said tongue and providing free space around the latter for digital access thereto.

3. A bottle seal comprising a cap consisting of a crown portion and a base portion, the former adapted to cover and prevent 80 access to the hermetic closure of the bottle and the latter adapted to be crimped upon the bottle neck, a ribbon portion disposed between and integral with said crown and base portions, respectively, and readily 85 severable therefrom for effecting separation thereof, said cap composed of thin sheet metal capable of being readily digitally bent and said ribbon bordered by incisions rendering the same readily severable from 90 the cap by digital engagement thereof, said ribbon terminating at one end in a digitally accessible tongue, there being an opening in the cap of greater area than said tongue 95 in which the latter is normally disposed, providing free space bordering said tongue.

4. A bottle-cap comprising a sheet-metal cup adapted to be inverted to receive the mouth portion of a bottle, the circumferential wall of said cup contiguous to the mouth 100 portion thereof adapted to be contracted about the bottle neck to secure said cap, the latter provided between its ends with an opening, parallel continuous incisions 105 extending circumferentially of the cap from one wall of said opening to the opposite wall thereof and bordering a strip of metal integral with and adapted to be severed from the cap for dividing the same into two 110 separable parts, said strip of metal terminating at one end in a free tongue projecting into said opening and spaced from the walls thereof to provide open spaces bordering both sides of said strip and between the free end thereof and the opposed 115 wall of said opening to thereby provide access to said tongue by a finger-nail for bending said tongue to project outwardly for digital engagement thereof, said tongue being of a length permitting the same to be 120 grasped between the tips of the thumb and index finger and said incisions being of a depth to effect weakening of the metal to an extent enabling the said strip to be torn out of the cap by digital engagement without 125 the use of tools or the like.

In testimony whereof, I have hereunto set my hand, this 2nd day of June, 1923.

WALTER A. STATTMANN.
